CASKET

William L. Waldron, Mesquite, Tex.

Application September 24, 1949, Serial No. 5,165

Term of patent 14 years

(Cl. D19—1)

To all whom it may concern:

Be it known that I, William L. Waldron, a citizen of the United States of America, residing at Mesquite, in the county of Dallas and State of Texas, have invented a new, original, and ornamental Design for Casket, of which the following is a specification, reference being had to the accompanying drawings, forming a part hereof.

Figure 1 is a side elevation of a casket showing my new design,

Figure 2 is a plan view of the same, and

Figure 3 is an end elevation of the casket with the wings folded.

The dominant features of my design reside in the portion shown in full lines.

I claim:

The ornamental design for a casket, substantially as shown and described.

WILLIAM L. WALDRON.
